US00D859850S

(12) **United States Design Patent** (10) Patent No.: **US D859,850 S**
(45) Date of Patent: ** Sep. 17, 2019

(54) **HAIR BRUSH**

(71) Applicant: **TANGLE TEEZER LIMITED**,
London (GB)

(72) Inventors: **Julian Leslie Meagher**, Hackney
London (GB); **Cameron Bruce**
William Treeby, London (GB)

(73) Assignee: **Tangle Teezer Limited**, London (GB)

(**) Term: **15 Years**

(21) Appl. No.: **29/668,437**

(22) Filed: **Oct. 30, 2018**

Related U.S. Application Data

(63) Continuation of application No. 35/502,952, filed on
Nov. 7, 2016 (U.S. filing date under 35 U.S.C. 384),
and having an international filing date of Nov. 7,
2016, now abandoned.

(57) **CLAIM**

The ornamental design for a hair brush, as shown and
described.

DESCRIPTION

FIG. 1 is a front perspective view of a hair brush in
accordance with our ornamental design;

FIG. 2 is a bottom plan view thereof;

FIG. 3 is a top plan view thereof;

FIG. 4 is a front elevation view thereof;

FIG. 5 is a right side elevation view thereof;

FIG. 6 is a rear elevation view thereof;

FIG. 7 is a left side view thereof; and,

FIG. 8 is a rear perspective view thereof.

1 Claim, 8 Drawing Sheets
